UNITED STATES PATENT OFFICE.

JAMES A. NOLAN, OF BOWERSTON, OHIO.

CONTROL MECHANISM FOR AUTOMATIC SAFETY MINE-CAR CAGERS.

1,254,622.

Specification of Letters Patent.

Patented Jan. 22, 1918.

Application filed September 30, 1916. Serial No. 123,147.

To all whom it may concern:

Be it known that I, JAMES A. NOLAN, a citizen of the United States, residing at Bowers-
ton, in the county of Harrison and State of
Ohio, have invented new and useful Im-
provements in Control Mechanism for Auto-
matic Safety Mine-Car Cagers, of which
the following is a specification.

This invention relates to safety devices
employed in connection with subterranean
chambers such as mine shafts and the like
and one of the objects of the invention is to
provide means whereby certain operating
mechanism which controls the movement of
the cars along a mine level may be rendered
operative or inoperative according to
whether or not the mine cage is to pass or
stop at a particular level.

As a rule mines are provided with differ-
ent levels leading into a vertical shaft in
which is a lift or cage. The cage is adapted
to be stopped by outwardly swinging sills or
beams which are carried by the wall of the
shaft. These beams are usually termed fans
or landers the latter term being preferable,
because they constitute the landings for the
cage whereby the cage will be supported at
any particular level by permitting the land-
ers to swing outwardly to form supports
or stops for the cage.

When it is desired to permit the cage to
pass the level or levels the landers are re-
tracted so as not to interfere with the verti-
cal movement thereof. The feeding of the
cars from the level onto the cage (which is
known as caging the cars) is now usually
accomplished by an automatic control mech-
anism such as is described in my applica-
tion Number 106,451, filed June 28th, 1916.

I have provided means whereby there may
be coöperative movement between the lander
and the car feeding mechanism so that when
the lander is swung up into inoperative pos-
ition the part of the feeding mechanism
which will ordinarily contact with the cage
will be moved out of operative position and
when the landers are swung outward the
cage contacting part of the car feeding
mechanism will be moved into operative po-
sition.

In the drawings:—

Figure 1, is a detail perspective view of
one end of an operating shaft and a lander.

Fig. 2, is an enlarged end view of an oper-
ating shaft and,

Fig. 3, is a detail perspective view of the
operating crank.

Referring now to the drawings by nu-
merals of reference I have used the same de-
signating numerals as I used in the above 60
mentioned application so that the structure
will be better understood.

The rails 1 and 2 are shown as resting
upon a sill 3, and this sill is provided with
a cut-out portion 4 to receive the bearing for 65
the shaft 23. On one end of the shaft 23 is
a bifurcated sleeve 4^a, secured thereto by a
bolt or other suitable fastening device 6. In
the bifurcated sleeve is a laterally swinging
crank or arm 7, on one end of which is a 70
laterally projecting crank member 8, having
an upstanding terminal lip 9. Underneath
the crank member 8, is a bearing 10, receiv-
ing a loosely swinging depending arm 11
which is at all times within the loop 12 on 75
the horizontal portion 13 carried by the
lander 14. It will be observed that when
the lander is in a vertical position the end
of the crank member 8, is retracted inwardly
beyond the bifurcated end of the shaft 23 80
and as this point is within the outer wall of
the lander the cage may pass up and down
without coming in contact with the operat-
ing mechanism, therefore the liability of the
shaft 23 being operated so as to trip a car or 85
release it through accident will be avoided.

When the lander is swung out to consti-
tute a landing so that the cage will rest
thereon the loop 12 will carry the swinging
arm 11 outward, and as a result the crank 90
member 8 will be moved out to operating
position so that when the cage reaches the
proper point of contact the part thereon
may strike against the member 8, and there-
by impart a rotative movement to the shaft 95
23 to operate the releasing and tripping
mechanism for the cars.

In Figs. 3, I have shown a lip 9 on the
member 8; this is to prevent the member 8
from slipping off the contacting element of 100
the cage when the arm 7 is in operative pos-
ition. When the lander 14 is moved back
into vertical position the arm 7 will again
be retracted into an inoperative position and
the cage may move past that particular level 105
without affecting any of the operating mech-
anism. Of course it is to be understood that
the shaft 23 is provided with a counter-
balance of the nature shown in my com-
panion application so that when the cage 110

moves off the member 8 the shaft 23 will be returned to its original position.

The advantage in loosely mounting the arm 11 is that it will assume a vertical position irrespective of the position of the arm 7, therefore it will at all times be in proper position for contact with the loop 12.

What I claim is:—

- 10 1. In a device of the class described, a rock shaft of a car operating mechanism, a bifurcated end on said shaft, a laterally swinging arm carried by the bifurcated end, a lander, and connections between the lander and the arm.
- 15 2. In a device of the class described, a rock

shaft of a car operating mechanism, a laterally swinging arm carried by said shaft, a transverse pin on said arm, a lip on the free end of said pin, landers, and a connection between the lander and the arm.

20

3. In a device of the class described, a rock shaft of a car operating mechanism, a laterally swinging arm on the end of the rock shaft having a right angular projection or pin, a lip on said pin, a freely swinging vertically disposed arm carried by the pin, a lander and a loop carried by the lander and receiving the freely swinging arm.

25

In testimony whereof I affix my signature.

JAMES A. NOLAN.
